UNITED STATES PATENT OFFICE.

FRIEDRICH HERRMANN, OF LINCOLN, NEBRASKA.

SHOE.

Application filed November 6, 1926. Serial No. 146,708.

This invention relates to shoes and more particularly to a shoe construction for preventing stretching or elongation of the shoe in such manner that it fails to fit properly around the instep of the wearer.

A further object of the invention is to provide a method of repairing old shoes, the leather of which has stretched to a point where the shoe no longer properly fits the ankle of the wearer, so that it will again properly fit.

A further object of the invention is to provide means for so repairing the shoe that the repairs are invisible and are not uncomfortable to the wearer.

These and other objects I attain by the construction shown in the accompanying drawings, wherein for the purpose of illustration is shown a preferred embodiment 20 of my invention and wherein:

Figure 1 is a plan view of a shoe, the vamp of which has stretched, so that it no longer fits;

Figure 2 is a similar view showing the 25 first step of the method completed;

Figure 3 is a perspective view showing the second step completed;

Figure 4 is a perspective view showing the 30 vamp as secured to the tape and shrunk into position thereon;

Figure 5 is a plan view of the shoe as completed;

Figure 6 is a perspective view showing a modified manner of applying the tape;

Figure 7 is a fragmentary sectional view 35 through the vamp of the shoe after the vamp has been secured to the tape.

Referring now more particularly to the drawings, the numeral 10 designates the 40 vamp of a low shoe which, immediately in advance of the counter 11, has bulges 12 caused by stretching of the material of the vamp. In order to remove the bulges in accordance with my invention, the lining 13 of the shoe is first separated from the 45 vamp and counter, all severed stitches being carefully removed. In this operation, care is taken not to stretch the lining. Two sections of unstretchable twill tape, pref- 50 erably of the same color as the shoe and of a length slightly greater than the chordal length of the bulge, are then prepared by placing rubber cement upon one face there- 55 of and allowing the tape to dry for about five minutes. While rubber cement is pre-

ferred, any cement may be employed which will not harden leather. Upon the opposed exposed portion of the inner face of the vamp and counter at the tops thereof, a band of cement is applied of the same 60 width as the tape and likewise allowed to dry for about five minutes. Each tape is then placed in the shoe with the cemented side next to the shoe, the top of the tape being flush with the top edge of the shoe, 65 so that in restitching the lining to the vamp and counter, the stitches will pass through the tape. These tapes are so stretched that they extend chordally of the bulges 12 and are firmly secured at their ends. The vamp 70 is then firmly pressed against the outer face of the tape, working from the forward ends of the tapes toward the rear ends thereof, until the tape adheres to the shoe and the leather of the shoe has been smoothly placed in position, as more particularly shown in Figure 4. After the tapes and vamp are properly joined, cement is placed 75 on the exposed side of the tapes and the lining replaced at once against the tape being worked into position until it is smoothly engaged therewith throughout the lengths of the tape. The vamp and counter are then sewed to the tape and lining to restore the shoe to its original condition.

While I have above called for the use of two tapes, one disposed at each side of the shoe, if desired, a single tape can be employed which is passed entirely about the counter of the shoe, as shown in Figure 6. 90 Where this construction is employed, if the tape is wide, it is often necessary to notch the lower edge thereof in order that the tape may not have uncomfortable engagement with the heel through the lining. While 95 this process has been described, as employed with a shoe which has been stretched in use, it may be employed with advantage in the fitting of new shoes which are loose about the heel or ankle. High shoes may 100 be cut down for use as low shoes and reconstructed by this process to fit closely about the ankle.

It will be obvious that a shoe embodying a tape positioned in accordance with the 105 above directions will be substantially unstretchable in the counter and will accordingly properly fit the foot at all times.

Since certain changes are possible in the 110 method hereinbefore described without de-

parting from the spirit of the invention, I do not limit myself to such a specific method except as hereinafter claimed.

I claim:-

- 5 1. The method of removing bulges caused by the stretching of the vamps of shoes consisting in providing a strip of unstretchable tape of slightly less length than that portion of the vamp forming the bulge, securing the ends of the strip to the shoe at the upper edge thereof so that the strip extends chordally of the bulge and causing the leather of the vamp to smoothly engage and adhere to said tape.
- 10 15. 2. The method of removing bulges caused by the stretching of the vamps of shoes consisting in providing a strip of unstretchable tape of slightly less length than that portion of the vamp forming the bulge, securing the ends of the strip to the shoe at the upper edge between the vamp and lining thereof so that the strip extends chordally of the bulge and causing the leather of the vamp and the lining to smoothly engage and adhere to said tape.
- 20 25. 3. The method of removing bulges caused by the stretching of the vamps of low shoes consisting in separating the lining from the vamp at and adjacent both sides of the bulge,

providing a strip of unstretchable tape of 30 slightly less length than that portion of the vamp forming the bulge, securing the ends of the strip to the vamp and counter of the shoe at the upper edge thereof so that the strip extends chordally of the bulge, causing 35 the leather of the vamp to smoothly engage and adhere to said tape, so that it smoothly engages the same and correspondingly connecting the lining to the tape.

4. The method of removing bulges caused 40 by the stretching of the vamps of low shoes consisting in separating the lining from the vamp at and adjacent both sides of the bulge, providing a strip of unstretchable tape of 45 slightly less length than that portion of the vamp forming the bulge, securing the ends of the strip to the vamp and counter of the shoe at the upper edge thereof so that the strip extends chordally of the bulge, causing 50 the leather to the vamp to smoothly engage and adhere to said tape, so that it smoothly engages the same and correspondingly connecting the lining to the tape and stitching 55 the vamp and lining to one another to the tape.

In testimony whereof I hereunto affix my signature.

FRIEDRICH HERRMANN.
